UNITED STATES PATENT OFFICE

ROSS E. RISSE, OF BONHAM, TEXAS, ASSIGNOR TO SOUTHWEST PUMP COMPANY, OF BONHAM, TEXAS, A CORPORATION OF TEXAS

DISPLAY DEVICE

Application filed May 18, 1928. Serial No. 278,862.

This invention pertains to new and useful improvements in display devices.

One object of the invention is to provide a display device which may be readily attached 5 to an open mesh support, in an improved and substantial manner.

A further object of the invention is to provide a hanger, capable of adjustment, which may be secured at any desired point on the 10 open mesh support, and when once placed in position, cannot be easily displaced and which will be rigidly held in place.

A still further object of the invention is to provide a holder for a changeable exhibitor 15 arranged to be removably mounted on the hanger, so that the exhibitor cannot be removed from the holder.

A construction designed to carry out the invention will be hereinafter described, together with other features of the invention. 20

The invention will be more readily understood from a reading of the following specification and by reference to the accompanying drawings, in which an example of the invention 25 is shown and wherein:

Fig. 1 is an elevation of an open mesh support having mounted thereon a display device constructed in accordance with the invention,

Fig. 2 is a view of the display device and the support, partly in elevation and partly in section,

Fig. 3 is a vertical sectional view taken on the line 3—3 of Fig. 2,

Fig. 4 is a horizontal cross-sectional view taken on the line 4—4 of Fig. 3, and

Fig. 5 is a detail of a guard strip for the frame.

In the drawings the numeral 10 designates 40 an elongated mounting strip and 11 an elongated locking strip telescoping into inclined flanges 12 along the edges of the mounting strip. Each strip has at its outer end a central tongue 13 offset rearwardly from a pair of lugs 14 between which it is located.

The strips are preferably made of comparatively heavy gauge sheet metal so that the parts are readily bent to shape, but they may be formed of other material. On its lower 50 end the locking strip 11 has an outwardly

bent step 15, notched to receive the flanges 12. The strips 10 and 11 constitute a hanger and in applying it to an open mesh support, such as a guard cylinder A for a liquid dispenser, the tongue 13 of the mounting strip 10 is engaged in one of the meshes. When said tongue is engaged in the said mesh, the component lugs 14 will rest upon the wires of the meshes, while the tongue will engage under the said wires, thereby affording a secure 60 support.

The locking strip 11 needs to be adjusted on the strip 10 so the tongue 13 at the upper end will engage in a mesh and the lugs will overlie the mesh wires. This can be readily 65 accomplished by holding the strip 10 with one hand and pushing upwardly on the step 15 with the other hand. The meshes may be slightly out of vertical alinement. To hold the strips in their adjusted positions, notches 16 are provided in the strip 10 for receiving 70 bosses 17 on the strip 11, thus forming a lock.

The rectangular frame 18 of a holder has lateral vertical flanges 19 along its rear edge which is slotted so that two plates of glass 75 20 or the like with an exhibitor plate 21 therebetween, may be slid into the frame. The exhibitor may be a sheet of cardboard, metal or other material, having the display on each side which it is desired to exhibit.

The holder is mounted on the hanger by sliding or telescoping the flanges 19 into the flanges 12 and resting the frame 18 on the step 15. When the holder is mounted on the hanger the slotted back of said holder will be 80 closed by the strip 11 and the flanges 19 engaging in the inclined flanges 12 will force the two strips together, whereby a compact and substantial structure will be had. This engagement will lock the bosses 17 in the 85 notches 16.

The device will be rigidly and prominently secured on the cylinder A and is easily and quickly placed or removed. When it is desired to change the exhibitor 21, the holder 90 may be slipped from the hanger and another exhibitor easily substituted.

In Fig. 5 a guard strip 22 is shown inserted within the flanges 12 and between the locking strip 11 and the frame flanges 19. 100

Such a strip will tend to more firmly hold the parts in their locked position. An outwardly directed lip 23 at the top of the strip 22 overhangs the frame and excludes water from passing down the rear of the frame and into its slot.

Various changes in the size and shape of the different parts, as well as modifications and alterations, may be made within the scope of the appended claims.

10 What I claim is:

1. In a display device, a hanger having means for mounting it in the meshes of an open mesh support and including a longitudinal member with a step at one end, and a display holder adapted to rest upon said step and having an interlocking flange engaging said member.

2. The display device defined by claim 1, and means for locking the hanger in position upon said support.

3. The display device defined by claim 1 in which the display holder is provided with an opening for inserting an exhibitor sheet disposed next said member.

25 4. In a display device, a hanger including telescoping strips having mesh engaging elements at their ends, a display holder, and means for slidably interlocking said holder with one of the hanger strips.

35 5. In a display device, a hanger comprising longitudinally adjustable members having means at their outer ends for mounting in the meshes of an open mesh support, and a display holder having means to slidably interlock with one hanger member so as to be removed therefrom without dislodging said hanger.

40 6. In a display device, a mounting strip having longitudinal flanges, a locking strip telescoping the flanges of the mounting strip, each strip having a mesh engaging tongue at its outer end, and a display holder including a frame having lateral flanges slidable into the flanges of the mounting strip.

45 7. In a display device, a mounting strip having longitudinal flanges, a locking strip telescoping the flanges of the mounting strip, each strip having a mesh engaging tongue at its outer end, a display holder including a frame having lateral flanges slidable into the flanges of the mounting strip, a support for the holder frame carried by the locking strip, and means for locking the strips together.

55 8. In a display device, a mounting strip having longitudinal flanges and mesh engaging elements at its lower end, a locking strip telescoping into the flanges of the mounting strip and slidable thereon, the locking strip having a step at its lower end and mesh engaging elements at its upper end, and a display holder including a frame having lateral vertical flanges engaging in the flanges of the mounting strip, whereby the frame is 60 rested upon the step of the locking strip.

9. In a display device, a mounting strip having longitudinal flanges and mesh engaging elements at its lower end, a locking strip telescoping into the flanges of the mounting strip and slidable thereon, the locking strip having a step at its lower end and mesh engaging elements at its upper end, a display holder including a frame having lateral vertical flanges engaging in the flanges of the mounting strip, whereby the frame is rested upon the step of the locking strip, and interlocking elements carried by the strips for securing the same in adjusted positions.

10. In a display device, a mounting strip having longitudinal flanges, a locking strip telescoping the flanges of the mounting strip, each strip having a mesh engaging tongue at its outer end, a display holder including a frame having lateral flanges slidable into the flanges of the mounting strip, and a guard strip inserted between the locking strip and the holder frame and having a lip overhanging the rear of the frame.

11. In a display device, a hanger including telescoping strips, means upon the abutting faces of said strips for locking them in adjusted position, a display holder, and means for slidably interlocking said holder with one of the hanger strips.

In testimony whereof I affix my signature.

ROSS E. RISER.
